UNITED STATES PATENT OFFICE.

HENRY K. PORTER, OF CHELSEA, MASSACHUSETTS.

DESIGN FOR A CUTTER-LEVER HANDLE.

No. 87,826.

Specification for Design.

Patented Feb. 13, 1906.

Application filed September 14, 1905. Serial No. 278,524. Term of patent 14 years.

To all whom it may concern:

Be it known that I, HENRY K. PORTER, a citizen of the United States, residing at Chelsea, in the county of Suffolk and State of Massachusetts, have invented a new, original, and ornamental Design for a Cutter-Lever Handle, of which the following is a specification, reference being had to the accompanying drawing, forming part thereof.

The figure is a perspective view of a cutter-lever handle, showing my new design.

I claim—

The ornamental design for a cutter-lever handle, as shown.

HENRY K. PORTER.
